(57) **CLAIM**

The ornamental design for a tibial button as shown and described.

DESCRIPTION

FIG. 1 is a top perspective view of a tibial button;
 FIG. 2 is a top plan view thereof;
 FIG. 3 is a bottom plan view thereof; and,
 FIG. 4 is a front elevation view thereof, the rear elevation view, the left side elevation view, and the right side elevation view being identical thereto.
 The dash-dot-dash broken lines in the drawings define the bounds of the claimed design and form no part thereof.

See application file for complete search history.
